UNITED STATES PATENT OFFICE.

LEWIS O'HARA, OF OSWEGO, NEW YORK, ASSIGNOR OF ONE-HALF TO DENNIS DONOVAN, OF SAME PLACE.

LIFTING-JACK.

SPECIFICATION forming part of Letters Patent No. 317,951, dated May 12, 1885.

Application filed March 18, 1885. (No model.)

To all whom it may concern:

Be it known that I, LEWIS O'HARA, of Oswego, in the county of Oswego, in the State of New York, have invented new and useful Improvements in Lifting-Jacks, of which the following, taken in connection with the accompanying drawings, is a full, clear, and exact description.

This invention relates to the class of lifting-jacks in which a screw is employed as the lifting-power.

The invention consists in an improved construction and combination of the constituent members of a jack possessing superior efficiency, stability, and convenience of operation.

The invention is fully illustrated in the annexed drawings, wherein Figure 1 is a side elevation of my lifting-jack. Fig. 2 is a vertical transverse section of the same, and Fig. 3 is a horizontal transverse section on line yy , Fig. 1.

Similar letters of reference indicate corresponding parts.

S represents the screw which is to furnish the lifting-power.

A represents the base of the jack provided with a screw-threaded socket, in which the lower end of screw S works, and B designates the top bearing, which may be either pivoted on the upper end of the screw in the usual manner or provided with a screw-threaded socket by which it is connected with the upper end of the screw S, having screw-threads running in opposite direction from those on the lower end of the screw. By the employment of this right-and-left screw, in connection with the screw-threaded base A and top bearing, B, the movement of the top bearing is accelerated to twice the speed of an ordinary screw-jack.

On the central portion of the screw S is rigidly secured a horizontal ratchet-disk, r, and above this disk is a collar, c, loosely connected with the screw, so as to allow it to freely turn thereon. Said collar is provided with a screw-threaded socket, a, standing radially in relation to the screw. With this socket is detachably connected a lever, l, having its ends

screw-threaded and entering the aforesaid socket. Back of the screw-threaded portion of the lever a smooth neck, n, and a shoulder, o, back of said neck, are formed on said lever. 50

On the neck of the lever l is pivoted a pawl, p, provided with an eye, e, which embraces the neck n and abuts against the shoulder o thereof, and against the exterior of the socket a, as illustrated in Fig. 2 of the drawings. 55 The said pawl is of such a form as to adapt it to engage with the ratchet r, and can be swung toward either side of the lever l to reverse the movement of said ratchet, which latter transmits a corresponding motion to the screw S. 60

It will be observed that the described connection of the lever l with the socket a and pawl p admits of a ready attachment and detachment of said lever and pawl when desired, and the connection of the pawl with the lever 65 is such as to securely guide said pawl in its operative position on the ratchet-disk.

Having described my invention, what I claim as new, and desire to secure by Letters Patent, is—

In combination with the screw S and ratchet r attached thereto, the collar c, loosely connected with the screw and provided with the screw-threaded socket a, the lever l, having a screw-threaded end detachably connected with 70 the socket a, and formed with the smooth neck n and shoulder o, back of the screw-threaded portion, and the pawl p, provided with the eye e, embracing the neck n and abutting against the shoulder o and exterior 75 of the socket a, substantially as described and shown.

In testimony whereof I have hereunto signed my name and affixed my seal, in the presence of two attesting witnesses, at Syracuse, in the 85 county of Onondaga, in the State of New York, this 9th day of March, 1885.

LEWIS O'HARA. [L. S.]

Witnesses:

W. C. RAYMOND,
F. H. GIBBS.
